[57] CLAIM

The ornamental design for a set of air deflectors for a vehicle, substantially as shown and described.

DESCRIPTION

FIG. 1 is a perspective view of a set of air deflectors for a vehicle showing our new design, it being understood that the broken lines are for illustrative purposes only; FIG. 2 is a side elevational view of the right side deflector to an enlarged scale; FIG. 3 is a top plan view thereof to an enlarged scale; FIG. 4 is a bottom plan view thereof to an enlarged scale; FIG. 5 is a rear elevational view thereof to an enlarged scale; and FIG. 6 is a side elevational view of the right side deflector taken along line 6—6 in FIG. 5.
